Specification for Design.

Patented Aug. 1, 1922.

Application filed December 3, 1921. Serial No. 519,774. Term of patent 3½ years.

To all whom it may concern:

Be it known that I, FRED WALTER, Jr., a citizen of the United States, residing at Los Angeles, Los Angeles County, California, have invented a new, original, and ornamental Design for Badge, Button, Emblem or Article of Similar Nature, of which the following is a specification, reference being had to the accompanying drawing, forming a part thereof.

Figure 1 is a plan view of a badge, button, emblem or article of similar nature showing my new design.

I claim the ornamental design for a badge, button, emblem, or article of similar nature as shown.

FRED WALTER, JR.
